SUPPORT FOR BEATERS OR MIXERS

Ernest C. Brullhardt, Stratford, N. J.

Application May 20, 1939, Serial No. 274,841

6 Claims. (Cl. 248—295)

The present invention is a holder or support for egg beaters or batter mixers.

Beaters of the type ordinarily used in a home have a handle which is grasped by one hand of the user for holding it in position in a bowl or the like, while the other hand turns, or otherwise operates, means for performing the beating or mixing operation. In these circumstances, the beater frequently slips out of position, resulting in the material being treated spilling out of the bowl, as well as other drawbacks occurring with which the housewife and cook is familiar.

The object of the present invention is the provision of a very simple and effective means by which beaters, of the above mentioned kind, may be removably supported in position, during use or otherwise, and may be adjusted to different positions to accommodate beaters of different sizes as well as to adjust the beater to various heights within the mixing bowl or container.

The invention also has as an object the provision of novel means by which the beater may be ready and releasably attached to it and held in a stable fixed operating position.

With the above objects in view, the invention further resides in the sundry features and details of construction, combination, and arrangement of parts hereinafter appearing as the invention is more specifically described and particularly pointed out in the appended claims:

In the drawing, which shows two preferred embodiments of the invention, as now devised:

Figure 1 is a side elevation of the invention in its applied position;

Figure 2 is an end view of the invention and looking in the direction of the arrow in Figure 1;

Figure 3 is a perspective view of the upper end of the support or holder and illustrating the beater attaching means;

Figure 4 is a sectional view through the beater attaching means and being taken substantially on line 4—4 of Figure 1; and

Figure 5 is a view similar to Figure 4 but showing a modification wherein the latch spring is omitted.

Referring more in detail to the drawing, wherein like characters refer to similar and like parts throughout the several views, H represents the support or holder which comprises a standard 10, preferably of strip metal, having a laterally extending arm 11 at its upper end and a clamp 12 at its lower end, and which clamp is preferably adjustable on the standard 10. The clamp 12 may be of any suitable construction for detachably mounting the holder on a ledge, table

or other place where the beater may be conveniently used. The standard is of a length sufficient to position the arm 11 at the desired height to support a beater or mixer M (shown in dotted lines in Figs. 1 and 2) in its normal relation, when in use, with a bowl B; and the arm 11 is of a length to extend over the bowl when the standard is secured in position.

For the purposes of present illustration, this clamp 12 takes the form of a U-shaped bracket, one leg of which has a thumb screw 13 threaded therein and carrying a clamping head 14 disposed opposite the other leg of the clamp. The closed end of the clamp is provided with a slot 15 through which the standard 10 extends and is held in vertically adjusted position by a thumb screw 16. The arm 11 is preferably provided by bending the upper end of the standard 10 laterally at right angles thereto, thereby forming a continuation of the standard 10.

The arm 11 is provided at its outer end with a hook means for releasably holding the beater or mixer M in position, and, since the arm 11 is shown as a continuation of the standard 10, it is preferred to twist, as at 17, the same so that the width of the end portion of the arm 11, which engages the mixer M, will normally extend in a substantially vertical position, thus also giving rigidity to the arm.

Most hand beaters or mixers generally in home use comprise a frame having a vertically extending strip of metal f and are also, in some uses, provided with two spaced openings o in the frame and which openings are invariably spaced a uniform distance apart.

One means for releasably attaching the mixer M to the holder comprises an offset keeper or strap 18 at one side of the free end portion of the arm 11 and which forms a vertical slot therewith to receive and removably retain the metal strip portion f of the mixer frame. The keeper preferably is a vertical strap having one lateral end secured to the arm 11, as at 19, and its opposite end having an inturned end 20 spaced from the adjacent side face of the arm 11, for a distance equal to the thickness of a portion f of a beater which may be moved therebetween.

This keeper or strap 18 is, however, preferably formed by striking the same out from the material which forms the arm 11, as particularly shown in Figs. 3, 4, and 5. By so doing the construction of the holder is economically produced and the keeper 18 is an integral part of the arm.

In order to frictionally latch the beater M in the keeper 18, a spring 18a is provided and it is

preferred that the spring 18a be a flat spring having one end d secured to the arm 11 adjacent the opening 18b formed by striking out of the keeper 18 and having its other end e extending through said opening 18b to lie in contact with or contiguous to the keeper 18 so that the frame portion of the beater M, inserted between the keeper 18 and the arm 11, will be moved by the spring 18a to the position shown in Fig. 4 where-
10 by the parts 19 and 20 of the keeper maintain the beater against swinging movement. The end e of the spring is preferably curved. As shown in Fig. 5, the spring 18a may be omitted and by moving and holding the beater by its handle so
15 that the portion f of its frame will contact the lip 20, the beater will be maintained against swinging or slipping on the bottom of the bowl B during operation.

The other means for releasably attaching the
20 beater or mixer M to the holder H comprises two spaced and vertically aligned studs 21 and 22 horizontally projecting from the extremity of the arm 11, one of the projections, preferably the upper projection 21, is provided with an up-
25 turned end 23. Hence a beater M provided with suitable spaced openings o, may be supported by the holder H by inserting the upturned ends 23 of the stud 21 into one of the openings o and, by swinging or moving the beater to a vertical
30 position, the other opening o may be brought to register with the stud 22 which can then be inserted thereinto, thus supporting the beater M against swinging movements when in operation. The beater or mixer M may be removed from
35 the holder H by a reverse operation.

Having thus described the preferred form of the invention and the manner in which it is performed, it is to be understood that the invention is not limited to the exact details of construction
40 shown and described, and is susceptible to various structures and modifications within the scope of the appended claims.

What I claim is:

1. A support for beaters or mixers comprising
45 a standard securable to a rigid object, said standard having a substantially horizontally extending part to overlie a bowl or the like, a lug carried by said part and having a portion thereof spaced and extending substantially parallel to said part
50 to form a slot having relatively wide side walls and in which slot a portion of the beater may be inserted, and means at the free end of the lug to at least partially close that end of the slot for preventing a swinging movement of the beater
55 when in said supported position.

2. Means for supporting a beater in proper relation to a mixing bowl or the like comprising substantially horizontal arm with a relatively

wide vertical surface, a keeper rigid with the arm and offset therefrom and having a surface substantially parallel with said surface of the arm to form a substantially vertical slot to receive therein a portion of the beater, one end of said keeper having a laterally and inwardly extending end spaced from the arm to permit the insertion of a portion of the beater therebetween, whereby said portion of the beater when inserted between the end portions of said keeper may be supported in operative position and prevented from swinging during operation.

3. In a support for mixers or beaters, a substantially horizontally extending arm adapted to overlie a mixing bowl or the like, an end portion 15 of said arm having a relatively wide vertically extending surface, a substantially horizontally extending lug struck from said arm at the portion thereof having said vertically extending surface and formed to provide a keeper offset from 20 said vertically extending surface of the arm, the free end of said keeper extending laterally of the keeper to form an inwardly projecting lip spaced from the said surface of the arm to permit the insertion of a portion of a beater or mixer there-
25 between, a spring carried by the arm and extending through the opening formed by the striking-out of said keeper and adapted to press, between said lip and the closed end of said keeper, that portion of the beater inserted into the keeper, 30 whereby the beater will be held in position against swinging movement when fully inserted into the keeper.

4. In a support for beaters or mixers, a supporting member having a pair of spaced laterally 35 extending studs projecting from a surface of said member and adapted to extend into complementary openings provided in the beater or mixer, one of said studs having an upwardly extending outer end.

5. In a support for beaters or mixers, a supporting member having a surface normally lying in a substantially vertical plane, a pair of spaced substantially horizontally extending studs projecting from said surface and arranged in a sub-
45 stantially vertical plane and adapted to inter-engage with complementary openings formed in the beater or mixer, the uppermost of said studs having an upturned outer end.

6. In a support for beaters or mixers, a supporting member having a surface normally lying in a substantially vertical plane, a pair of spaced substantially horizontally extending studs projecting from said surface and arranged in a sub-
50 stantially vertical plane and adapted to inter-engage with complementary openings formed in the beater or mixer.

ERNEST C. BRULLHARDT.
